UNITED STATES PATENT OFFICE

141,182

DESIGN FOR AN ASH TRAY OR THE LIKE

Herbert R. Levinger, Chicago, Ill.

Application January 8, 1945, Serial No. 117,343

Term of patent 14 years

(Cl. D85—2)

To all whom it may concern:

Be it known that I, Herbert R. Levinger, a citizen of the United States, residing at Chicago, in the county of Cook and State of Illinois, have invented a new, original, and ornamental Design for an Ash Tray or the Like, of which the following is a specification, reference being had to the accompanying drawing, forming a part thereof.

In the drawing—

Fig. 1 is a top plan view of the ash tray or the like showing my new design,
Fig. 2 is a side elevational view, and
Fig. 3 is a vertical sectional view.

I claim:

The ornamental design for an ash tray or the like, substantially as shown.

HERBERT R. LEVINGER.
